UNITED STATES PATENT OFFICE

136,280

DESIGN FOR A PEN HOLDING STAND

William Tate Holland, Marietta, Ga.

Application November 28, 1942, Serial No. 108,899

Term of patent 3½ years

To all whom it may concern:

Be it known that I, William Tate Holland, a citizen of the United States, residing at Marietta, in the county of Cobb and State of Georgia, have invented a new, original, and ornamental Design for a Pen Holding Stand, of which the following is a specification, reference being had to the accompanying drawing, forming part thereof.

I claim:

The ornamental design for a pen holding stand, as shown.

WILLIAM TATE HOLLAND.
